UNITED STATES PATENT OFFICE.

HUGH B. LINCOLN, OF ELECTRA, TEXAS.

VALVE MEANS FOR OIL-WELL SWIVELS.

1,217,467.

Specification of Letters Patent. Patented Feb. 27, 1917.

Application filed December 27, 1916. Serial No. 139,224.

To all whom it may concern:

Be it known that I, HUGH B. LINCOLN, a citizen of the United States, residing at Electra, in the county of Wichita and State of Texas, have invented a new and useful Valve Means for Oil-Well Swivels, of which the following is a specification.

My invention relates to the art of drilling oil wells, and more particularly to the art of drilling oil wells by the so-called rotary system, in which a string of drill pipe carrying a bit at its lower end is rotated in the hole by suitable power driven means. In this system, a mud laden fluid is pumped downwardly through the drill pipe, emerging through suitable holes in the bit at the bottom of the hole, and serving to retain the walls of the well and hydrostatically balance any pressures existing in the well.

It is common practice in the art of drilling to wholly or partially support the upper end of the string of drill pipe in a swivel, this swivel being supplied with water through a flexible pipe.

The principal object of my invention is to provide valve means which are incorporated in the swivel for the purpose of expediting and simplifying the drilling of wells, as will be hereinafter explained.

In the drawings, which are for illustrative purposes only:

Figure 1 is a side elevation, partially in section, of a portion of the apparatus used in the rotary system.

Fig. 2 is a vertical section, on an enlarged scale, of a goose-neck, such as is employed in the swivel in such a system.

Fig. 3 is a plan view of the goose-neck shown in Fig. 2.

In the form of the invention illustrated in these drawings, an oil well 11 is shown in the process of being drilled, a derrick 13 being built over the well, this derrick having a floor 14 on which is placed a rotary table 15 which is driven by suitable power means, not shown.

Passing through the rotary table 15 is the upper end of a string of drill pipe 16 which carries a suitable bit 17 at its lower end, this bit being provided with perforations 18 through which the mud forced downwardly through the drill pipe 16 may be forced into the well.

In some methods of using the rotary system, the table 15 is provided with grips which clamp directly upon the drill pipe.

In other forms of the system, a square or groove stem is used on the upper end of the drill pipe, and my invention is applicable to either method of drilling. In either case, 60 a swivel 20 is secured to the upper end of the pipe, this swivel being supported by a bail 21 from a hook 22, the hook 22 being secured by means of a bail 23 to suitable hoisting cables and hoisting apparatus, not 65 shown. Secured on the top of the swivel 20 is a goose-neck 24, this goose-neck being secured to a stationary pipe 25 which projects down inside the drill pipe 16 and is provided with suitable stuffing boxes, not 70 shown, to prevent the loss of mud around the joints. Secured to the goose-neck 24 is a flexible hose 26, the other end of the hose 26 being secured to a stand-pipe 27 which is connected to the pressure side of a mud 75 pump 28, the mud pump drawing mud laden fluid through a pipe 29 from a small well or sump 30, into which the mud rising in the well overflows. A relief valve 31 is provided on the lower end of the stand-pipe 27. The goose-neck 24 is provided with a check valve, as shown in Fig. 2, the upper limb of the goose-neck 24 being tapped, as shown at 32, and having a plug 33 screwed therein. The plug 33 is provided with a plurality of 80 holes 34, normally closed by a valve 35, this valve sliding on a stem 36 formed in the plug 33, and being held on its seat by a spring 37, the other end of which abuts on a diaphragm 38. The diaphragm 38 has a 85 hole 39 in the center thereof somewhat larger than the stem 36.

The method of operation of the invention is as follows:

The pipe 16 is rotated by the table 15 by means of the grips 19, a portion of the weight of the pipe being carried on the swivel 20. Mud laden fluid is supplied to the upper end of the pipe through the flexible hose 26 and the stand-pipe 27 from the mud pump 28, this mud laden fluid passing downwardly through the pipe 16, outwardly through the openings 18 and upwardly through the well 11, and overflowing into the sump 30, from which it is taken by the suction pipe 29 into the pump 28. The pressure required to circulate mud laden fluid may be considerable, and this pressure acts in conjunction with the spring 37 to hold the valve 35 firmly on its seat, thus closing the 110 openings 34.

Whenever it is desired to disconnect sec-

tions of the drill pipe 16, which must be done frequently for the purpose of removing bits, or adding sections to the string of pipe, considerable inconvenience results from the ordinary methods of drilling in which no check valve 35 is provided. The water contained in the upper sections of the drill pipe 16 and the flexible hose 26 tends to remain in these sections, as there is no means of letting air into the top of the pipe to displace the water, and this water remains in the pipes until a second opening is made by breaking another joint, at which time it comes out all at once, flooding the floor of the derrick and greatly increasing the hazards of operating, especially in very cold weather.

In my invention, the check valve 35 will remain open to admit air into the goose-neck 24 when a partial vacuum is formed therein, so that water is readily drained from the drill pipe 16 and the flexible hose 26 and stand-pipe 27 by opening the valve 31, the water in the flexible hose 26 and stand-pipe 27 flowing outwardly through the valve 31, and the water in the drill pipe 16 falling to the level of the water in the well 11 in the sump 30.

By the use of my invention there is no

danger of water being trapped in the upper portions of the apparatus, and practically no water finds its way to the floor of the derrick.

I claim as my invention:

1. In combination; a string of drill pipe; 35 swivel means for supporting the upper end of said pipe; a flexible hose for supplying mud laden fluid under pressure to the upper end of said pipe; means for connecting said flexible hose to said pipe; and a check valve 40 in the upper portion of said means, said check valve being so arranged that it will open to admit air to said pipe only when the pressure in said pipe falls below atmospheric pressure. 45

2. In a swivel; a goose-neck having one limb formed to connect to pipe members which are in open connection with a string of drill pipe, and having its other limb formed to connect through a flexible hose 50 with a mud pump; and a check valve in said goose-neck so arranged as to admit air to the interior of said goose-neck only when a partial vacuum is formed in said goose-neck.

In testimony whereof, I have hereunto set my hand at Los Angeles, California, this 16th day of December, 1916.

HUGH B. LINCOLN.
